FLOW CONTROL MEANS IN REFRIGERATING APPARATUS

Albert O. Grooms, Dayton, Ohio, assignor to General Motors Corporation, Dayton, Ohio, a corporation of Delaware

Application December 11, 1946, Serial No. 715,569

9 Claims. (Cl. 62—4)

1

This invention relates to refrigerating apparatus and more particularly to means for controlling the flow of refrigerant from the condenser to the evaporator.

In addition to hand valves there are four common types of refrigerant flow control devices, namely high and low side floats, expansion valves and restrictors. No one of these appears to be ideal from every standpoint. A considerable loss in efficiency of a refrigerating system is entailed by improper liquid flow. Some of this loss is caused when liquid flows from the condenser to the evaporator during the idle period of the system. A loss in efficiency may also be caused when the evaporator receives too much or too little refrigerant at any time during the operating period of the system.

It is an object of my invention to provide a satisfactory control and flow of liquid refrigerant to the evaporator at all times during the operating period of the refrigerating system.

It is another object of my invention to provide an equalization of pressure between the high and low sides of the system during the idle period only without permitting the flow of liquid.

It is another object of my invention to provide an arrangement whereby the flow of refrigerant to the evaporator begins when the system starts operating.

These objects are attained by providing a refrigerating system employing a high side float control having a hollow valve stem. The interior of this stem is closed when the liquid level in the float chamber is high and it is opened when the liquid level in the float chamber is low to permit the equalization of gas during the idle period of the compressor. The float chamber enclosure is of non-magnetic material but the float itself is of a magnetic material. An electromagnetic coil connected in series with the phase winding is provided for magnetically lifting the float during the starting period of the motor to prevent initial starvation of the evaporator during the operating period.

Further objects and advantages of the present invention will be apparent from the following description, reference being had to the accompanying drawing, wherein a preferred form of the present invention is clearly shown.

In the drawing:

The figure shows a sectional view of a high side float embodying my invention, together with the remaining portions of the compression refrigerating system.

Referring now to the drawing, there is shown

1 a compressor 20 for withdrawing evaporated refrigerant from the evaporator 22 and for forwarding the compressed refrigerant to a condenser 24 where the compressed refrigerant is liquefied. Connected between the condenser 24 and the evaporator 22 is a high side float valve embodying my invention. This high side float valve has a casing of non-magnetic material such as copper, brass or bronze including a lower shell body 28, and an upper shell body 30, together with a brass inlet connector 32 and a brass outlet connector 34. These parts are preferably bonded together by silver soldering or other suitable means.

2 The upper and lower connectors 32 and 34 are each provided with guides 36 and 38 each including four guiding prongs. The upper guide 36 guides the valve seat 40 mounted upon a hollow valve stem 42 while the lower valve guide 38 guides the valve 44 mounted upon the lower end of this same hollow valve stem 42. The valve 44 is adapted to seat upon a seat provided at the mouth of the outlet passage 46 in the outlet connector 34. The upper valve seat 40 is movable and is adapted to be closed when it moves upwardly into engagement with the stationary valve needle 48 provided on the inlet connector 32. The inlet connector 32 has branch inlet passages 50 permitting the liquid to flow from the condenser 24 into the interior of the float valve 26 at all times.

The float is made in two halves of thin hot rolled steel. The lower half 52 is mounted upon a shoulder at the upper end of the valve 44 and the upper half 54 telescopes over the lower half 52 and is supported by a sleeve 56 upon the hollow valve stem 42 and extending to the valve seat member 40. This assembly may be brazed or soldered or welded together. Since the walls of the float are very thin to secure light weight, the interior of the float is preferably filled with a gas such as hydrogen, under sufficient pressure to prevent collapse of the float under the highest pressure expected to be encountered at any time. A small amount of a volatile liquid or vapor may be used instead of the gas if it has the proper pressure temperature characteristics to provide sufficient internal pressure to balance the highest refrigerant pressure encountered. The float is provided with the sealing tube 58 through which the float is charged with gas or vapor and then sealed.

Wrapped around the upper shell body 30 is an electromagnet coil 60 which is connected in series with the phase winding 62 of the electric motor

64. The other end of the electromagnet coil 60 is connected through the conductor 66 and the contacts 68 of the starting relay 10 to the supply conductor 72. The supply conductor 72 through the operating coil of the relay 10 is connected to the main winding 74 of the motor 64. The common junction of the main and phase windings 74 and 62 is connected to the thermostatic switch means 76 which controls the connection with the other supply conductor 78.

In operation, when the evaporator 22 reaches a predetermined high temperature, the snap-acting switch 76 will close causing current to flow from the supply conductor 78 through the main winding 74 and the coil of the starting relay 10 to the other supply conductor 72. The energization of the relay 10 will close the contacts 68 thus energizing the phase winding 62 and the electromagnet coil 60. This substantially simultaneously causes the starting of the motor 64 and the operation of the compressor 20 as well as causes the electromagnet coil 60 to magnetically attract the float 52, 54 of the high side float to lift the valve 44 to open position and to raise the valve seat member 40 into contact with the valve 48 to prevent the flow of gas through the hollow valve stem 42.

As soon as the motor reaches a sufficient speed, the starting relay 10 will open to deenergize the phase winding circuit including the electromagnet coil 60. The electromagnet 60 will not be energized until the next starting period of the motor 64. Thus at all other times the float valve will operate in accordance with the liquid level within the float chamber. However, the magnetic lifting of the float 52, 54 will permit a supply of liquid to flow into the evaporator 22 at the beginning of operating cycle to insure that sufficient liquid is present in the evaporator to assure immediate evaporation and cooling. In a short time, the compressor and condenser will supply sufficient liquid to the float chamber to lift the float in the usual manner to assure a normal supply of refrigerant to the evaporator 22.

To assure equalizations of the pressures during the idle period of the system, the valve stem 42 has been made with a very small hollow bore. When the operation of the compressor ceases liquid will continue to flow from the float chamber until the level is reduced sufficiently to permit closing of the valve 44. This will prevent continuation of the liquid flow. Restricted gas flow, however, is permitted by the lowering of the upper valve seat 40 to permit high pressure gas from the condenser 24 and the float chamber to flow slowly through the hollow valve stem 42 directly into the outlet passage 46. As is plainly evident from the drawing, the hollow valve stem 42 continues directly through the valve 44 to the outlet passage 46 so that gas flow is permitted even though valve 44 is in the closed position. This permits equalization of pressures between the condenser 24 and the evaporator 42 by the flow of gas. This equalization of pressures permits the use of a motor with low starting torque without any other form of unloading device. The hollow valve stem functions without interfering with the operation of the valve 44, and the closing of the upper end of the hollow valve stem during the operating period prevents any loss in efficiency due to the passage of uncondensed vapor into the float chamber. As the pressure differences are small, the problem of

making this additional valve for preventing gas flow is not difficult.

Through this arrangement efficient liquid flow control is obtained together with equalization of pressures during the idle period. Starving of the evaporator and flow of liquid into the evaporator during the idle period are minimized so that efficient performance of the system is obtained yet the system can be manufactured at a relatively low cost, since a low starting torque motor can be used. The high side float construction controls the liquid supply during the operating period to the best advantage.

While the form of embodiment of the invention as herein disclosed, constitutes a preferred form, it is to be understood that other forms might be adopted, as may come within the scope of the claims which follow.

What is claimed is as follows:

1. Refrigerating apparatus including compressing, condensing and evaporating means, a float controlled valve means for controlling the flow of liquid refrigerant from the condensing to the evaporating means, and means for conducting refrigerant gas from the condensing to the evaporating means when said valve means is closed and for preventing the flow of gas when said valve means is open.

2. Refrigerating apparatus including compressing, condensing and evaporating means, a float controlled valve means for controlling the flow of liquid refrigerant from the condensing to the evaporating means, said float controlled valve including a casing having an inlet and an outlet, a float within the casing having a valve for closing the outlet, means providing a gas passage by-passing said valve, and a second valve controlled by said float for closing said gas passage.

3. Refrigerating apparatus including compressing, condensing and evaporating means, a high side float control for controlling the flow of liquid refrigerant from the condensing means to the evaporating means, said float control including an electromagnet coil wound about said casing and a float in the form of a hollow member having wall portions of magnetic material located in the magnetic field of said electromagnet coil and constituting an armature for said electromagnet coil, said casing having wall portions of non-magnetic material adjacent said electromagnet coil, an electric motor for driving said compressing means, and control means for said motor and said electromagnet coil.

4. Refrigerating apparatus including compressing, condensing and evaporating means, a float controlled valve means for controlling the flow of refrigerant from the condensing to the evaporating means, said float controlled valve means including a casing having an inlet and an outlet, a float member within the casing provided with a means for closing said outlet, said float member having a gas passage extending through it to said outlet, said casing being provided with closing means cooperating with said float member for closing said gas passage when said float member is in the position wherein the outlet is open.

5. Refrigerating apparatus including compressing, condensing and evaporating means, a float controlled valve means for controlling the flow of refrigerant from the condensing to the evaporating means, said float controlled valve means including a casing having an inlet at the top and an outlet at the bottom, a float member within

the casing provided with a valve means at its lower end for closing said outlet, said float member being provided a gas passage extending from its upper portion to said valve means to discharge into said outlet, said casing being provided with closing means cooperating with said float member for closing said gas passage when said valve means is in the open position.

6. Refrigerating apparatus including compressing, condensing and evaporating means, a high side float control for controlling the flow of liquid refrigerant from the condensing to the evaporating means, electrically operated means for opening said float control, an electric motor for driving the compressing means, said motor having a starting circuit arrangement for accelerating the motor from an idle condition to the switching speed range which is less than the normal running speed of the motor, said motor also having a running circuit arrangement for accelerating the motor above the switching speed range for operation at the normal running speed, said electrically operated means being electrically connected to said starting circuit arrangement so that it is energized whenever the starting circuit arrangement is energized and is deenergized whenever the starting circuit arrangement is discontinued, and a starting control for energizing said starting control arrangement and said electrically operated means whenever the motor is operating below the switching speed range, said starting control being provided with automatic circuit changing means responsive to the operating condition of the motor in the switching speed range for simultaneously deenergizing said electrically operated means and changing the starting circuit arrangement to the running circuit arrangement when the motor passes through the switching speed range during acceleration.

7. Refrigerating apparatus including compressing, condensing and evaporating means, a high side float control for controlling the flow of liquid refrigerant from the condensing to the evaporating means, electrically operated means for opening said float control, an electric motor for driving the compressing means, said motor having a starting circuit arrangement for accelerating the motor from an idle condition to the switching speed range which is less than the normal running speed of the motor, said motor also having a running circuit arrangement for accelerating the motor above the switching speed range for operation at the normal running speed, and a starting control for simultaneously energizing said electrically operated means and said starting circuit arrangement upon each start of the motor, said starting control being provided with automatic circuit changing means responsive to the operating condition of the motor in the switching speed range for simultaneously deenergizing said electrically operated means and changing the

starting circuit arrangement to the running circuit arrangement.

8. Refrigerating apparatus including compressing, condensing and evaporating means, a float controlled valve means for controlling the flow of refrigerant from the condensing to the evaporating means, said float controlled valve means including a casing having an inlet at the top and an outlet at the bottom, a float member within the casing provided with a valve means at its lower end for closing said outlet, said float member being provided a gas passage extending from its upper portion to said valve means to discharge into said outlet, said float member being provided with an upwardly extending tubular extension forming the upper end of said gas passage, the upper end of said extension being provided with a valve seat surface, said casing being provided with guide means and an upper valve member for guiding said extension into contacting and closing engagement with the upper valve member to close the upper end of said gas passage when said float member rises to lift its valve means at its lower end to the open position.

9. Refrigerating apparatus including a low side comprising evaporating means and a high side comprising compressing and condensing means and a high side float control for controlling the flow of liquid refrigerant from the high side to the low side, electrically operated means for admitting liquid refrigerant to the low side from the high side, an electric motor for driving the compressing means, said motor having a starting circuit arrangement for accelerating the motor from an idle condition to the switching speed range which is less than the normal running speed of the motor, said motor also having a running circuit arrangement for accelerating the motor above the switching speed range for operation at the normal running speed, and a starting control for simultaneously energizing said electrically operated means and said starting circuit arrangement upon each start of the motor, said starting control being provided with automatic circuit changing means responsive to the operating condition of the motor in the switching speed range for simultaneously deenergizing said electrically operated means and changing the starting circuit arrangement to the running circuit arrangement.
